DAMPER FOR WARM AIR FURNACES

Filed Oct. 22, 1928

UNITED STATES PATENT OFFICE

RALPH S. McNANEY, OF DOWAGIAC, MICHIGAN, ASSIGNEE TO DOWAGIAC STEEL FURNACE COMPANY, OF DOWAGIAC, MICHIGAN, A CORPORATION OF MICHIGAN

DAMPER FOR WARM-AIR FURNACES

Application filed October 22, 1928. Serial No. 314,232.

The invention relates to warm air furnaces and more particularly to a construction of direct draft damper arranged in the radiator between the combustion chamber and the smoke flue.

One of the objects of the invention is to improve the radiator construction to provide for proper baffling of the flue gases to obtain the maximum efficiency.

Another object is to provide a direct draft damper operable from outside the radiator and so constructed and arranged that the radiator is gas-tight where the operating rod passes therethrough.

A further object is to provide a composite construction formed of sheet metal and cast metal parts welded together to form a substantially seamless construction and provided with special means for eliminating leakage around the damper operating mechanism.

These and other objects are attained by providing the novel construction hereinafter more fully described and illustrated in the accompanying drawings, wherein

Figure 1 is a central longitudinal section through the furnace;

Figure 2 is an enlarged section through the damper operating mechanism;

Figure 3 is a section on the line 3—3 of Figure 2.

In the construction illustrated in the drawings, the fire pot and combustion chamber of the furnace is formed by a sheet steel drum 10 having a dome-shaped head 11 electrically welded thereto and having a fire door extension 15. The particular construction of the fire pot forms no part of the present invention, and will not be described in detail as it is more fully set forth in my co-pending application, Serial No. 314,209 filed on even date herewith.

23 represents the radiator of the furnace which consists of a segmental body portion 35, having upper and lower heads 36 and 37 welded thereto. For joining the radiator to the combustion chamber there are two cast metal collars 24 and 25, each of which is flanged at 30 in order that they may be detachably united by bolts 31. The collars 24 and 25 are constructed of cast steel to enable

them to be welded to the sheet steel radiator and drum, respectively, thereby forming a strong, seamless construction. A liner 32 of cast iron is inserted within the collars to protect the latter from the hot products of combustion. 55

Within the radiator 23 is a baffle or deflector plate 40 arranged in an inclined position to extend from a point closely adjacent the inner wall and near the lower end of the radiator to the top of the radiator near the middle thereof. The baffle 40 is also a curved section so that its opposite edges are adjacent to the outer wall of the drum, thereby causing the gaseous product which passes from the drum 10 into the radiator 23 to be deflected to the opposite sides thereof and downward and then upward through the center of the drum to the escape flue 38. To permit of direct draft when firing the furnace and thereby prevent the products of combustion from escaping into the basement area through the feed door, there is a damper 41 located in an opening in the baffle which is in alignment with the nipple or collar 24 and flue 38. 60

This damper is hinged at 42 and is weighted so as to automatically close by gravity. In case of a sudden explosion of combustible gases in the drum 10, the damper 41 can automatically swing open and allow 65

the gases to pass directly into and through flue 38, rather than pursue their regular course downward and then upward around baffle 40 with a possibility of blowing open door on clean-out 39 and distributing soot, smoke and ashes in basement area. To open 70

the damper 41 mechanically there is provided a vertical rock shaft 43 having an arm 44 adapted to bear against the damper at a point below its hinge pivots 42. Located on the rock shaft 43 and electrically welded thereto 75

is a flat steel washer 43^a which seals the opening in a bearing 45 where rock shaft 43 enters, to prevent the products of combustion from finding their way out into the casing area. 80

The bearing 45 in which the rock shaft is journaled is preferably formed of cast steel in

order that it may be welded to the sheet steel radiator and thus make a tight joint. The

bearing 45 has a flange 46, the underside of 85

100

which is welded to the head 36 of the radiator. The top face of the flange has a series of raised rings 47 with annular recesses 48 therebetween into which is fitted a complementary part 49 with a series of rings 50 arranged in the recesses 48. The part 47 is fixed to the rock shaft 43 by a set screw 51 and is provided with a lever 52 for actuating the rock shaft and adjusting the damper. 5 A rod 53 extends from the lever to the front of the furnace and provides a convenient handle for opening the damper before opening the fire door. While the bearing 45 is of cast steel, the cooperating part 47 is preferably of cast iron since it does not require welding. Leakage through the damper operating means is effectively prevented by reason of the large number of bearing surfaces formed by the concentric rings 47 and 50 and 10 by the close contact of the bearing member 45 and the washer 43a.

What I claim as my invention is:

1. In a furnace, a sheet metal radiator, a damper therein, operating means for said damper extending through said radiator and a bearing of cast metal having substantially the same expansion coefficient as said sheet metal and welded thereto.
2. In a furnace, a radiator, a hollow bearing integrally united thereto, a head on said bearing provided with a series of concentric rings and intermediate recesses, a shaft extending through said bearing and a cap for said shaft comprising rings engaging the recesses in said head.
3. In a furnace, a steel radiator, a hollow cast steel bearing welded to said radiator, a rod extending through said bearing, a lug on said rod seating against one end of said bearing, the other end of said bearing having raised rings thereon with intermediate annular recesses and a cap secured to said rod and having complementary rings engaging the recesses of said head, thereby forming a tight joint.
4. In a furnace, a sheet steel radiator, a baffle therein, a direct draft damper in said baffle, a rotatable rod for operating said damper having one end projecting through said radiator, a cast steel bearing for said rod welded to said radiator, a collar on said rod engaging the inner end of said bearing, a cap secured to said rod outside of said radiator, said cap having a series of annular flanges with intermediate recesses and a head on said cast steel bearing having complementary annular flanges and recesses cooperating with said cap to form a leak-proof joint.

In testimony whereof I affix my signature.

60 RALPH S. McNANEY.
